UNITED STATES PATENT OFFICE

2,561,567

WRINGER

Clayton F. Emmert, Newton, Iowa, assignor to
Automatic Washer Company, Newton, Iowa, a
corporation of Delaware

Application September 19, 1945, Serial No. 617,196

10 Claims. (Cl. 68—253)

1

This invention relates to wringers constructed and designed for use in connection with any type of domestic washing machine or automatic laundry unit requiring wringers.

One of the main objects of the present invention is to provide a wringer of compact construction with a substantial minimum overall vertical height and which includes all of the safety features for safe operation and one that fulfills and efficiently carries out all of the functions required by a standard wringer machine.

Another object of the present invention is to provide a wringer of the type described which embodies a safety release mechanism efficiently adapted and constructed for use in this small vertical height wringer.

The design of the present wringer embodies a construction wherein the usual upper or top frame has been eliminated and the structure incorporates as another object of the invention the novel arrangement of using the shaft of the upper roll to function as the upper frame so that this upper roll structure and its associated parts provide a means to absorb the reactionary force between the rolls created by the pressure means and by the clothes as the latter are passed between the rolls.

A further feature of the present wringer is the introduction of a release bar so shaped and arranged to comprise a wringer top and to coact with the main wringer frame to complete the wringer housing. Such a wringer top comprises a release bar connected with the safety release mechanism for the purpose of operating the latter. Since this release bar forms the wringer top and extends substantially the full length of the wringer, it is disposed in the best possible position to be operated by a reflex action of the user in the event that the latter should accidentally get his or her hand caught in the wringer rolls. The natural tendency would be to thrust forth the free hand against the wringer which would be the wringer top and this particular action supplies more than enough force necessary for releasing the latch mechanism which permits separation of the wringer rolls at the instant that the release bar is touched.

In connection with the object immediately above, it is another feature of the present wringer to include a drive mechanism which has separable members that drive the wringer rolls and which members are parted at the instant that the safety release mechanism is operated by contact with the release bar top of the wringer so that the drive is simultaneously interrupted with

2

the parting of the wringer rolls under the action described.

There are other features and advantages associated with the wringer of the present construction such as providing a latch mechanism which is constructed to include means for limiting the exploding act of the wringer as occurs through the operation of the wringer top release bar. Other advantages and features not already referred to will appear in the following description of the wringer construction having reference to the accompanying drawings illustrating a preferred embodiment thereof.

In the drawings:

15 Fig. 1 is a side elevational view of the wringer structure incorporating the present invention;

Fig. 2 is a plan view of the wringer as shown in Fig. 1 with parts thereof broken away and in section to illustrate certain details of construction;

10 Fig. 3 is a general longitudinal vertical sectional view taken through the wringer structure substantially as viewed along the line 3—3 in Fig. 2;

Fig. 4 is a fragmentary view taken substantially 20 along the line 4—4 in Fig. 3 to illustrate the drain board and flume structure.

Fig. 5 is an end view of the wringer as seen from the left in Fig. 1, with certain parts thereof illustrated in section to clarify certain details of 30 construction of the release mechanism;

Fig. 6 is an enlarged cross sectional view of the mechanism of the left end of Fig. 3 to clarify the mechanism arrangement and connection of the safety release latch means and the reset mechanism associated therewith;

Fig. 7 is a diagrammatic view of the wringer structure in longitudinal section illustrating such wringer rolls of the structure as separated and parted upon operation of the top release bar of 40 the wringer to release the latch mechanism;

Fig. 8 is an enlarged end view of the top release bar together with the shaft of the upper roll which constitutes the upper frame in this wringer structure;

45 Fig. 9 is a sectional view of the top release bar as taken substantially along the line 9—9 in Fig. 7;

Fig. 10 is a side elevational view of the wringer top release bar per se;

50 Fig. 11 is a plan view of the trough portion of the main or base frame also showing the channel structures associated therewith for guiding the lower roll bearing blocks;

Fig. 12 is a side elevational view of the structure shown in Fig. 11;

Fig. 13 is an end view of the structure illustrated in Figs. 11 and 12 as viewed from the latch and reset end of the wringer.

Figs. 14 and 15 are face and edge views respectively of the release catch actuator of the latch mechanism.

Figs. 16 and 17 are face and edge views respectively of the reset lever latch unit;

Fig. 18 is an outside face view of the reset lever per se;

Fig. 19 is a central cross sectional view of the reset lever substantially as viewed along the line 19-19 in Fig. 19;

Fig. 20 is a transverse cross sectional view of the reset lever as taken along the line 20-20 in Fig. 18;

Fig. 21 is a cross sectional view of the driven end of the upper wringer roll;

Fig. 22 is a cross sectional view of the driven gear which connects with the driven end of the upper drive roll illustrated in Fig. 21; and

Fig. 23 is a small diagrammatic cross sectional view of a three roll wringer structure designed to incorporate a wringer top release bar of the same nature as illustrated in the preferred form of wringer to which the other figures in the drawings are directed.

Referring to Figs. 1, 2 and 3, the main body or housing structure of the wringer consists of a gear case 1, a projecting framework structure 2, a wringer top 3, with suitable drain boards 4 and 5 connected with the latter and a tiltable flume 6 positioned under the drain boards 4 and 5 and adapted for draining the water from the projecting framework 2. The framework 2 and the gear case 1 together are the main elements forming the lower frame or base frame of the wringer, and the gear case 1 is provided with a vertical pedestal or depending base 7 carrying a spring pressed index pin 8 releasable by operating the finger lug 9 for angularly locating the entire wringer and its pedestal 7 in predetermined angular position upon the wringer post of a washing machine.

The projecting framework 2 may be of any conventional construction but in the present wringer it is made substantially as illustrated in Figs. 11, 12 and 13. This projecting frame 2 is provided with a trough 10 as the main structural element thereof which is adapted for catching the water from the wringer rolls and draining the same out of suitable openings 11 which lead directly into the flume 6. Suitable channels 12 and 13 are connected with the ends of the trough 10 in a manner shown in Figs. 11 and 12 and provide the end portions of the lower wringer frame. The channel section 13 is provided with suitable openings 14 through which screws such as 15 in Fig. 3 are inserted for securing the entire frame 2 to the gear casing 1 making the two parts substantially integral and for all purposes constituting the lower and main frame of the wringer. Each of the channel sections 12 and 13 provide guides 16 and 17 respectively for the reception of the bearings 18 and 19 connected with shaft 20 of the lower wringer roll 21 of the wringer. The lower roll 21 is constantly urged upwardly by the leaf spring 22 extending the length of the roll and engaging the undersides of the bearing blocks 18 and 19 as shown in Fig. 3. Spring 22 is adjustably secured to the base frame by means of the bracket 23 and screw 24 engaging the threaded bushing 25 fixedly secured to the trough bottom. By turning the screw 24, the tension of the spring 22 against the

bearing blocks 18 and 19 and the roll 21 can be maintained.

The upper frame of the wringer is best illustrated in Fig. 3 and is indicated generally by the reference numeral 26 comprising a non-rotatable shaft 27 pivotally supported upon the pivot pin 28 extending between ears 29 mounted upon the top of the gear casing 1; while the other or free end of the shaft 27 is normally held in place by means of the safety release mechanism 30 which is mounted on the extended end of the lower or base frame 2 of the wringer. The shaft 27 rotatably supports the upper roll 31 and maintains this roll in positions for rotation about the axial center line of the shaft 27 holding such roll in this position for all normal operation of the wringer, the lower roll 21 moving toward and away therefrom under the resilient action of the spring 22 as previously described.

The upper wringer roll 31 is provided with a tubular core 32 having bushings 33 and 34 within the ends thereof for rotating upon the upper frame structure comprising the shaft 27. Movement of the upper roll 31 to the left is prevented by means of the washers 35 and 36 and the spacer 37, the washer 35 being carried in the groove 38 in the shaft 27. The right hand end of the upper roll as viewed in Fig. 3 and as better illustrated in Fig. 21 is constructed with the tubular core 32 of the roll 31 projecting beyond the right hand end of the roll to receive and securely carry a bushing 39 provided with slots 40.

The drive gear for the upper roll as best seen in Figs. 3 and 22 comprises a gear 41 secured to a sleeve 42 providing a bearing for riding upon the shaft 27, such sleeve being made to fit into the bushing 39 with projections 43 thereon adapted for engaging within the slots 40 of the bushing 39. This gear drive unit illustrated in Fig. 22 is prevented from moving to the right with respect to the shaft 27 as shown in Fig. 3 by means of the washer 44 nested within the annular groove 45 formed about the shaft 27.

The drive to the wringer rolls may be of any conventional construction including certain features to be described for interrupting the drive to the wringer rolls wherein the power drive to the rolls is interrupted responsive to the separation of the rolls when the latter are released by the user of the wringer. Fig. 3 illustrates a preferred construction of drive mechanism entirely housed within the gear case 1. This wringer drive mechanism includes a main drive shaft 46 vertically journalled in the casing 1 and connected with coupling 47 into which the main drive shaft 48 extends as it comes from the wringer column and from the connected washing machine driving mechanism. Spaced pinions 49 and 50 are loosely journalled upon the shaft 46 and are maintained in the relation to each other illustrated in Fig. 3 by means of a yoke 51 that is vertically shiftable by means of the eccentric pin 52 carried by the stub shaft 53 which may be rotated to various angular positions by means of a handle 54 and located in such positions by the detent mechanism 55 that operates with corresponding depressions in the face 56 of the handle.

Both of the pinions 49 and 50 are disposed to mesh with the teeth of the crown gear 51 carried upon the horizontal stub shaft 53. When the pinions 49 and 50 are in the position illustrated in Fig. 3 wherein the handle 54 is in upper position, both of these gears are inactive. By rotating handle 54 in one direction or the

other, the pinions 49 and 50 will be moved together vertically with respect to the shaft 46. Movement of the handle in one direction will cause the pinions to be lowered wherein pinion 49 will engage the upper drive pin 59 by means of the slot 60 thereby imparting a drive to the crown gear 57 and shaft 58 in one direction. By shifting the handle 54 oppositely to raise both of the pinions 49 and 50, the slot 61 of the lower pinion 50 will contact or engage the lower drive pin 62 to drive the crown gear 57 in the reverse direction thereby reversing the rotation of the wringer rolls to accommodate feeding the clothing through the wringer from the opposite direction to that first described.

A drive gear 63 is secured to the hub of the crown gear 57 and adapted for rotation with the stub shaft 58, the gear 63 being in position to mesh with the upper roll drive gear 41 thereby transmitting the drive from the shafts 46 and 48 directly through either one of the pinions 49 and 50 through the crown gear 57 and up to the upper wringer roll as best illustrated in Fig. 3.

A forked operating arm 64 having suitable friction means 65 coacting with the shaft 58 cooperates with the reverse turned end 66 of an actuator rod 67 which is connected with the flume 6 through suitable brackets 68 and 69 best illustrated in Figs. 3 and 4, the brackets 69 being secured to the upper side of the trough 10 of the base frame. With this arrangement, the rotation of shaft 58 in one direction or the other will impart limited movement to the arm 64 by means of the frictional bearing structure 65 causing the forked arm 64 to tilt the flume 6 in one direction or the other direction depending upon the direction of rotation of the wringer rolls whereupon the water will always be drained to the proper side of the wringer.

The safety release mechanism generally indicated at 30 and previously referred to comprises the means for positioning the upper wringer frame 26 in predetermined relation with respect to the base frame of the wringer and includes latch mechanism instantly releasable through manual operation for parting the wringer rolls to prevent injury to the user in the event that a hand is accidentally drawn into the rolls while operating the wringer. The safety release mechanism including the releasable latch structure is best understood by referring to Figs. 3, 6 and 5 and comprises a reset lever 70 pivoted on a pin 71 projecting through the vertical legs of a yoke 72 which is secured within a slot 73 in the shaft 27 by means of the fastening screw 74. This reset lever 70 is also pivotally connected by means of the pin 75 with a toggle link 76 pivotally supported from a pin 77 passing through the two ears 78 forming an integral part of the channel member 12 of the main base frame 2, such ears being illustrated in Figs. 11, 12 and 13.

As the reset lever is swung downwardly and inwardly toward the wringer from any position such as that one illustrated in Fig. 7, this reset lever is latched into the position illustrated in Figs. 3 and 6 by means of the catches 79 snapping into position over the pair of latches 80 forming an integral part of the latch bar 81. The general details of the construction of the reset lever 70 are well illustrated in Figs. 18, 19 and 20 while the latches 80 and the associated latch bar 81 are illustrated in more detail in Figs. 16 and 17.

The latch bar 81 is supported for vertical sliding movement upon the outside face 82 of the channel 12 as best shown in Figs. 12 and 13 and 78

guided thereon by means of the pin 83 and the machine screw assembly 84. The upper end of the latch bar 81 is provided with a slot 85 and the prongs 87 are for straddling the pin 83 while an elongated hole 88 is used for accommodating the machine screw assembly 84 permitting limited vertical movement of the latch bar 81 with respect to the adjacent portion of the base frame unit comprising the channel member 12. A tension spring 89 is interposed between the fixed pin 83 and an ear 90 of the latch bar to always hold the bar in its uppermost position as determined by the length of the elongated opening 88 therein. When the bar is in this position, the catch 79 of the reset lever is always in operative latching engagement with the latch 80 of the latch bar 81 holding the safety release mechanism and its associated parts in the respective positions shown in Figs. 3 and 6.

20 A latch bar actuator is pivotally supported upon the screw unit 84 and located on the inside of the channel 12 and arranged for limited swinging movement about the pivot point established by the screw 84. This actuator 91 is in the form 25 of a triangular plate having laterally extending ears 92 and 93 shown in Fig. 5 flanking the upper end thereof. The intermediate portion of the actuator 91 carries a pin 94 which is adapted to project through the arcuate slot 95 in the channel 12 and cooperates with the cam slot 96 formed in the latch bar 81. The upper central portion of the actuator 91 is cut away as at 97 to provide sufficient clearance between the actuator and the shaft 27 of the upper frame. Obviously, angular tilting of the actuator about its pivot point comprising the screw 84 will cause the pin 94 to urge the latch bar 81 downwardly releasing the catches 79 from the latches 80 through which action the wringer explodes causing the upper wringer frame and its associated roll to move upwardly and away from the lower roll as illustrated in Fig. 7 thereby separating the rolls for withdrawal of any foreign object or the hand in the event of an accident. In this 45 same connection, it should be noted in Fig. 7 that the release of the latch bar 81 causes the gear 41 to disengage from the gear 63 interrupting the drive to the upper wringer roll and consequently to both rolls in view of the out-of-contact relationship created when the rolls are separated as in Fig. 7.

The angular shifting of the actuator 91 will move the latch bar 81 downwardly whether such actuator is shifted toward the left or toward the 55 right as viewed in Fig. 5. Motion is imparted to the actuator in either direction by manually engaging the wringer top 3 which comprises a release bar in this wringer construction. The wringer top 3 extends the full length of the wringer and is adapted to move vertically directly with the upper wringer frame comprising the shaft 27 whenever the release mechanism is operated to separate the rolls. This release bar comprising the wringer top 3 is secured to the 60 right hand end of the shaft 27 as shown in Fig. 3 by means of a suitable fastening screw 100, while the free end of the wringer top 3 best illustrated in Figs. 8 and 9 is provided with a suitable spring strap 101 having a detent portion 102 adapted to engage the shaft 27 as shown in these figures. The end of the release bar 3 is cut away as shown in Fig. 3 at 103 and is provided with an inturned ledge 104 for riding on top of the shaft 27 causing frictional line contact of the 65 wringer top 3 with the shaft 27. This ledge 104

coacts with the spring 101 to maintain the forward end of the release bar wringer top 3 in its cooperative position with respect to the shaft 27 and also in aligned relationship with the lower wringer frame to complete the entire wringer exterior as shown in Figs. 1 and 2.

Slight movement is necessary to displace the wringer top 3 sufficiently to engage the actuator ears 92 and 93 which are made to engage the lateral sides of the wringer top 3 as shown in Fig. 5 through which action the tilting or angular shifting of the actuator imparts movement to the latch bar 81 for releasing the latch mechanism to throw the wringer rolls apart and to discontinue the drive to the upper wringer roll as shown in Fig. 7. During the release action of the wringer it should be noted in Fig. 7 that the ultimate vertical swinging movement of the upper frame and the upper roll is limited by means of the link 76 which prevents separation of the upper wringer frame from the base frame of the wringer beyond a predetermined maximum amount.

In all cases, however, whenever the reset lever is operated to again relatch the mechanism for holding the upper and lower frames in operative relation to cause contact between the wringer rolls, the top 3, comprising the release bar will resume its normal centralized position with respect to the base frame by means illustrated in Figs. 8 and 9 and through the inherent resiliency of this top member, such action being controlled by the connection of the top member against the flat end of the shaft 27 through the fastening screw 100. Furthermore, it should be noted that the release bar comprising the wringer top 3 is of very light construction and merely comprises a housing unit for covering the upper portion of the wringer and to enclose the roll chamber which is provided by the lower open base frame construction. This centralizing or positioning of the top in proper alignment with the wringer base structure is also aided through the spring 89 which lifts the latch bar vertically causing the pin 94 of the actuator to drop into central relationship with respect to the cam slot 96 in the release bar 81. Thus the spring action described causes the actuator 91 to resume its vertical position with the ears 92 and 93 centralizing the wringer top 3 into the position shown in Fig. 5 with respect to the balance of the wringer structure. Therefore, the release bar comprising the wringer top 3 may be shifted sideways in one direction or the other and laterally with respect to the length of the wringer in one direction or the other to cause a release of the safety mechanism, and such release bar 3 moves directly upward with the vertically swinging upper frame comprising the shaft 27, this entire combined unit moving about the pivot 28 which is mounted upon the lower frame by means of the ears 29 that comprise an integral part of the gear casing 1. A very compact wringer structure is hereby produced having a small overall vertical height minimizing the effort which must be expended by the housewife in reaching over the top of the wringer while feeding clothes thereto or guiding the same away therefrom. Also if a wringer of this type is installed in a standard washing machine wherein a wringer column is employed for using the tube itself of the washer for housing the wringer, such a wringer would be well adapted as a disappearing wringer in view of the fact that the necessary vertical motion for nesting the wringer is considerably reduced.

because of the small overall vertical dimension of this wringer.

It is obvious that other arrangements may be produced incorporating the features embodied in the wringer of the preferred construction herein described and illustrated. Fig. 23 merely shows another adaptation of the present wringer design wherein a three roll wringer is diagrammatically shown. This construction shows the same upper roll 31 rotatably mounted upon the shaft 27 comprising the upper frame, such upper roll cooperating with a pair of lower rolls 106 and 107 urged vertically by means of any suitable leaf springs such as 108 and 109 respectively mounted within the lower or base frame 110 of the wringer structure. In this design of wringer a release bar 111 comprising the wringer top is adapted to cooperate with the general design of the wringer base 110 and also overlies the length of the wringer to be manually actuated laterally with respect thereto in either direction in the same manner as the wringer top 3 for cooperating with the release means of the safety latch mechanism to automatically part the wringer rolls upon manual contact of the wringer top 111.

It is obvious that modifications and changes may be made in the exact design and structure herein disclosed and described without departing from the spirit and scope of the present invention. Furthermore, equivalent mechanisms may be substituted to function in the manner as the mechanisms shown so that the invention is not to be limited to the specifically described disclosure excepting insofar as shall be determined by the breadth and scope of the appended claims submitted herewith.

What I claim is:

1. A roll wringer comprising a main frame, upper and lower rolls, means for guiding the lower roll relative to said main frame, a non-rotatable shaft for said upper roll and having one end pivotally connected with said main frame and having the other end free, releasable latch means to hold the free end of said shaft and the supported upper roll in predetermined relation with respect to the lower roll, pressure means carried by said main frame and acting upon one of said rolls to hold both rolls in active operative contact with each other, said rolls being separable, upon release of said latch means, through the pivoting of said upper roll shaft, and drive means for said rolls including cooperative drive members, one of said members being carried upon said shaft and connected to rotate said upper roll, the other of said members being operatively mounted in fixed position with respect to said main frame, and said drive members being separable upon movement of said non-rotatable shaft about its main frame pivot.

2. In a roll wringer, a lower frame forming the main body of the wringer and providing a chamber, upper and lower rolls operating within said chamber, said lower roll being mounted for movement relative to said lower frame, a shaft for said upper roll providing an overhead frame to hold said upper roll in position to be contacted by the lower roll, means to urge the lower roll against said upper roll, and cooperative means connected with the ends of the upper roll shaft to releasably hold the upper roll in normal operative position, said cooperative means including a manual release bar, and said bar being shaped to enclose the chamber of the lower frame and to cover the upper roll.

3. In a wringer, a base frame, upper and lower

rolls, cooperative means carried by said base frame to guide the lower roll and to urge same upwardly respectively, a shaft providing an upper frame to rotatably support the upper roll, said frame shaft having one end pivotally supported upon the base frame, releasable latch means connecting the other end of said shaft with said base frame to normally hold said upper roll in fixed position with respect to the base frame, said releasable latch means comprising latch mechanism, and a manual release bar shaped to form a top housing to enclose said upper roll and to coat with said base frame to complete the wringer housing, said bar acting to release the latch means when displaced laterally with respect to the wringer structure.

4. In a wringer, a lower frame, a spring pressed roll carried by said lower frame, an upper frame having a fixed pivotal connection with said lower frame for vertical swinging movement of the upper frame, said upper frame comprising a shaft carrying an upper roll, latch mechanism to normally position said upper and lower frames in fixed relation with respect to each other with the rolls in operative contact, and a manual release bar extending the length of the lower frame, said release bar being connected with said upper frame shaft to move vertically therewith but arranged to shift laterally with respect to said shaft, manual shifting of said bar causing release of the latch mechanism to separate the rolls.

5. In a wringer, a lower frame, a spring pressed roll carried by said lower frame, an upper frame connected with said lower frame to swing vertically comprising a shaft carrying an upper roll, latch mechanism to normally position said upper and lower frames in fixed relation with respect to each other with the rolls in operative contact, and a manual release bar extending the length of the lower frame, said release bar being connected with said upper frame shaft to move vertically therewith but arranged to shift laterally with respect to said shaft, manual shifting of said bar causing release of the latch mechanism to separate the rolls, and said latch mechanism having means to limit the upward throw of the upper frame shaft and its connected release bar upon operation of the latter.

6. An upper frame for wringers comprising a shaft having a fixed pivotal connection with the main wringer frame for swinging movement of the shaft in a vertical plane, said shaft carrying an upper wringer roll for cooperation with a lower roll, latch means to hold said shaft in a position to keep the rolls in operative contact, and release mechanism having a release bar connected to move with the shaft and arranged to release the latch means when moved laterally with respect to the shaft and the main frame of the wringer.

7. In a wringer having a gear casing, a trough like base attached at one end to said gear casing, a lower roll journalled in said trough-like base, said gear casing having ears at its top, a shaft pivoted at one end to said ears and having its other end free for upward swinging movement, an upper roll journalled upon said shaft for cooperation with the lower roll, a latch lever hinged to the free end of said shaft, a vertically

slidable latch bar upon an end of said base, said lever and bar having cooperating latching means for normally maintaining said rolls in operative relation, yielding means for normally urging said latch bar into latching position, an actuating lever having an operative connection with said latch bar for moving the same to unlatching position, said actuating lever having laterally extending wings, and a housing over said upper roll having parts for engaging said wings for actuating said actuating lever for releasing said latch lever.

8. In a wringer having a gear casing, a trough-like base attached at one end to said casing, a shaft having one end pivoted to said casing and having its other end free, an upper roll journalled in said trough-like base, yielding means for urging said rolls into cooperative relation, a latch lever hinged to the free end of said shaft, a slideable latch bar upon the adjacent end of said base, said latch bar and latch lever having cooperating latching means, and an actuating lever having a connection with said latch bar for moving said latch bar to unlatching position when said actuating lever is moved in either of two directions.

9. In a wringer, a lower roll, an upper roll, a shaft supporting the upper roll for relative rotation with respect thereto, means for pivotally supporting one end of said shaft, a latch lever pivoted to the other end of said shaft, means for latching and unlatching said latch lever comprising a lever having lateral wings, and a casing extending over the upper roll and having parts adapted for engagement with said wings for shifting said last mentioned lever for the purpose set forth.

10. In a wringer, a gear casing, a trough-like base connected at one end to said casing, a lower shaft journalled in said base, an upper shaft pivoted at one end to said casing and having its other end free, an upper roll journalled upon said upper shaft, a hood extending over said upper roll and secured to said upper shaft, a latch lever hinged to the free end of said upper shaft, a slideable latch bar on said base, said latch lever and bar having inter-engageable latching elements, and an actuating lever having a connection with said latch bar and having parts extending within said hood for the purpose set forth.

CLAYTON F. EMMERT.
